UNITED STATES PATENT OFFICE

154,194

DESIGN FOR A DOLL

Emile L. Adams, Piedmont, Calif., assignor of one-half to Ernest E. Adams, Piedmont, Calif.

Application August 21, 1947, Serial No. 140,981

Term of patent 3½ years

(Cl. D34—4)

To all whom it may concern:

Be it known that I, Emile L. Adams, a citizen of the United States and a resident of Piedmont, county of Alameda, and State of California, have invented a new, original, and ornamental Design for a Doll, of which the following is a specification, reference being had to the accompanying drawing, forming part thereof.

Figure 1 is a front elevational view of a doll, showing my new design.

Figure 2 is a rear view of the doll.

Figure 3 is a side view of the doll.

The detail of the body of the doll has been partially omitted in Figures 2 and 3 for convenience in illustration.

I claim:

The ornamental design for a doll, substantially as shown and described.

EMILE L. ADAMS.
